ELIAS E. RIES, OF NEW YORK, N. Y., ASSIGNOR, BY DIRECT AND MESNE ASSIGNMENTS,
TO THE SIMPLEX LETTER OPENER COMPANY, OF NEW YORK, N. Y., A CORPORATION
OF NEW YORK.

DEVICE FOR OPENING ENVELOPS.

1,005,879.

Specification of Letters Patent. Patented Oct. 17, 1911.

Application filed July 25, 1910. Serial No. 573,733.

To all whom it may concern:

Be it known that I, ELIAS E. RIES, a citizen of the United States, and a resident of New York, in the county of New York and State of New York, have invented certain new and useful Improvements in Devices for Opening Envelops, of which the following is a specification.

My present invention relates to devices or machines for opening envelops, the object being to provide an improved device with which envelops can be opened without danger of cutting or mutilating the contents.

Further objects are to attain a device which will, after one envelop has been opened, automatically return to its initial position to be ready for use with another envelop and to provide means for limiting the movement of the cutting device so that when 20 in its initial position it will be in position to act on the next envelop inserted.

A still further object is to provide a receptacle into which the clippings, due to operating the device, will be deposited.

Still further objects of the invention will be apparent from a reading of the subjoined description, among which are the means for retaining the operating parts of the device at all times in the same relation 30 to each other by compensating for the wear on the parts due to continual use.

Heretofore it has most commonly been the practice to open envelops by cutting the end with scissors or inserting a knife or other sharp instrument under a flap and ripping it open although various devices or machines have been proposed for opening envelops which, however, have not come into commercial use to any extent owing to various objections, which it is the object of my invention to overcome. In using scissors care has to be taken to see that the contents are not near the side or edge to be cut, which makes the operation of opening the envelops a time consuming one. By inserting a knife or other form of opener the danger of also ripping a letter, check or the like, which may be in the envelop, is ever present.

By the use of a device constructed in accordance with this invention, the cutting edge is always in correct position to operate on an envelop and envelops may be opened with great rapidity as the location of the

contents is a matter of no moment, the device merely cutting an exceedingly thin strip from the folded edge of the envelop and in fact merely cutting off the fold in the paper of the envelop. The cut made is so slight that it is impossible for the contents of the envelop to get far enough into the fold at a side or edge of the envelop to be cut by the opener.

In the accompanying drawings, Figure 1 is a front elevation of a machine constructed in accordance with the preferred manner of carrying my present invention into effect. Fig. 2 is a plan of the same. Fig. 3 is a plan view of a modified form. Fig. 4 is an end elevation of the form shown in Fig. 1. Fig. 5 is a transverse vertical section through the device taken on the line X X Fig. 1. Fig. 6 is an enlarged section taken on the line Y Y Fig. 1 and looking in the direction of the arrow A.

1 indicates a plate or base upon which the various parts of the machine are mounted.

2, 3 indicate standards rising from the base 1 at or near either end. A steel cylinder or cutter 4 longitudinally disposed with respect to the base is mounted on a shaft 5, 80 the exposed ends of which are journaled in and supported by the standards 2, 3. For facility and cheapness in constructing, the cylinder is preferably made a separate part and suitably secured to the shaft 5 to rotate 85 therewith, but, if desired, the cylinder and shaft might be integral. The shaft 5 extends for a suitable distance beyond both the standards 2, 3, and is provided on one of these exposed ends with a removable operating 90 handle 6 by means of which the cutter cylinder 4 is rotated.

For convenience of right or left hand operation (when the device is operated by hand for instance) or for other purposes, the handle 6 can be secured to either end of the machine by merely slipping it on and fastening it to the exposed end of the shaft at the desired end. The cylinder 4 has an inclined longitudinally or spirally disposed knife edge 7 which is preferably formed by cutting or milling a groove of the desired depth in the periphery of the cylinder the cutting side of the groove preferably being radially formed. The depth of the groove determines 100 the amount of material cut from the envelop

and is properly made shallow so that but a very thin strip will be cut. The knife edge may run the entire length of the cylinder as shown in Fig. 3 or it may stop somewhat 5 short and gradually merge into the periphery of the cylinder near the ends as shown in Fig. 1. When forming the knife edge as 10 shown in Fig. 1, a smooth periphery is left at both ends of the cylinder, the ends having the same diameter as the cylinder. When 15 the knife edge runs the entire length of the cylinder as in the form shown in Fig. 3 a collar 8 is provided at each end of the cylinder, the diameter of the collar being such that its periphery will be farther back than the depth of the cut in the cylinder.

9 indicates a steel cutting table or bed preferably as long as the cutter cylinder 4 and horizontally supported by and adapted 20 to slide on blocks 10 on the base 1, the upper surface or cutting edge of the table 9 being preferably located below the axis of the cutter cylinder 4, so that on rotating the cutter to sever an edge of the envelop, the under- 25 cut of the knife edge will be exaggerated and only the outer edge of the knife engage the envelop. The table is preferably so disposed on account of the difficulty of undercutting the edge when milling the cylinder to form 30 the knife.

11, 12 indicate guide plates secured in this instance to the sides of the blocks and overhanging and resting on the upper surface 35 of the cutting table to hold the same down on the blocks. The guides serve to limit the place of insertion of the envelop whereby the envelop cannot be presented to the cutter beyond the knife edge. In the form shown in Fig. 1 the guides are located on the 40 surface of the bed in such position that they prevent the envelop from engaging the cylinder at any part of the inclined surface caused by the knife groove merging into the periphery of the cylinder, whereby it is as- 45 sured that the entire length of the envelop presented to the cutter will be opened. In the form shown in Fig. 3 the guides 11, 12 are in the form of blocks fastened to the top surface of the cutting table and located so 50 that the side of the envelop to be opened cannot get beyond the end of the knife and they thereby prevent the envelop being but partially cut. In this form the table is held down upon the blocks by the heads of screws 55 passing through guide slots in the envelop guide blocks 11, 12 and table, and tapped into the top of the fixed supporting blocks 10. The table or bed 9 in both forms is loosely seated on the blocks 10, and its cutting edge is pressed toward the cylinder 4 by springs 13 preferably located at both ends 60 of the table, one end of the springs being secured to the table and the other to the fixed block 10. In the form shown in Fig. 1 the 65 ends of cutting edge of the table normally

bear against the periphery of the cylinder at the ends thereof thereby fixing the relation of the cutting edge of the table to the knife, so that when the cylinder is rotated the knife edge 7 wipes past the cutting edge 70 of the table just as in a pair of scissors, the knife progressively cutting the edge of the envelop. In the form shown in Fig. 3 the relation between the cutting edges is fixed by reason of the fact that the table bears or 75 engages indirectly against the collars through the guide blocks 10, engaging the periphery of the collars 8, the ends of the guides being in contact with the periphery of the collars when the cutting edge of the bed is in proper position to be closely wiped by the knife edge 7. In both cases any wear of the knife edge due to continued rotation of the cylinder is represented by a like amount of wear on the surfaces against 80 which the cutting edge of the table or the ends of the guides, as the case may be, bear and consequently the springs always keep the cutting edge of the table in exact position for the knife edge and thereby take up 85 and compensate for any wear on the parts. Also by having the cutting edge of the table pressed against the knife edge a self-sharpening action of the knife is produced, as by the close wiping of the edges on each 90 operation of the cylinder a sharpening effect of the knife edge must necessarily result. If the table or bed 9 were fixedly mounted continued use would wear the edges and eventually a space would be formed between 95 the cutting edge of the table and the knife edge whereby the efficiency of the device would be impaired and in time the knife would not cut.

Longitudinal displacement of the table 105 may be prevented by any suitable means as for instance in the form shown in Fig. 1, by the upright portion 14 of the guide plates 11, 12, by means of which they are fastened to the sides of the blocks 10. In the form 110 shown in Fig. 3, it is attained preferably by causing the side of the projecting ends of the guides to engage the ends of the cylinder 4.

Referring more particularly to Fig. 6, 15 indicates a stop which projects laterally 115 from the standard 3 and 16 indicates a co-acting pin secured to the cylinder 4 in a recess formed in the end thereof. On rotating the cutter cylinder forward a sufficient distance so that the knife 7 has cut the entire length of the envelop, the handle 6 is released and the cylinder is returned to its original position by a spring 17 one end of which is secured to the standard 2 and the other to the cylinder 4. On the return move- 120 ment the cylinder comes to rest when the pin 16 strikes the stop 15 at which time the lowermost edge of the knife is above the table or bed 9 ready for insertion of an envelop. Also preferably a stop is provided 130

to limit the forward rotation of the cylinder as for instance a pin 18 secured in the recess in the end of the cylinder 4 strikes the stop 15 after the knife edge has traversed the entire length of the cutting edge of the table 9.

19 indicates a hollow receptacle or box for which the base 1 of the machine serves as a cover and to which it is hinged along the back edge. A slot 20 formed in the base 1 and arranged below the meeting or cutting edges of the cylinder 4 and table 9 is of a length at least equal to the length of the cutting edges whereby the strip or edge cut from the envelop will drop down through the slot 20 and into the receptacle 19, thereby avoiding the necessity of gathering up the small strips of paper as a result of using the machine.

20 If desired the machine can be operated by a foot treadle by means of a chain 21 secured to the operating handle 6, the other end being secured to the usual form of treadle. Also the machine might be operated by motive power by providing suitable gearing on the shaft 4 coupled to a driving motor.

What I claim as my invention is:

1. In an envelop opener, the combination of a loosely mounted cutting table or bed 30 upon which the envelop is placed, a knife and means for automatically maintaining the relation of the cutting edge of said table or bed to the knife under conditions of wear.

2. In an envelop opener, the combination 35 of a knife, a table or bed upon which the envelop is placed and having a cutting edge in definite relation with said knife and springs for automatically maintaining said relation under conditions of wear.

40 3. In an envelop opener, the combination of a rotary cutter and a loosely mounted table or bed having a cutting edge pressed against said cutter.

4. In an envelop opener, the combination 45 of a rotary cylinder provided with a spiral cutter and a table upon which the envelop is placed and having a cutting edge spring-pressed against said cylinder whereby a self-sharpening of the knife edge will be effected on each operation of the cutter.

5. In an envelop opener, the combination of a rotary cylinder, a spiral groove in the periphery of said cylinder forming a knife edge and a co-operating cutting table.

55 6. In an envelop opener, the combination of a rotary cylinder, a spiral groove in the periphery of said cylinder forming a knife edge, the cutting side of said groove being radially disposed and a cutting table or bed disposed below the axis of said cylinder whereby the undercut of said knife edge is accentuated.

7. In an envelop opener, the combination 65 of a rotatable cylinder, a spiral knife edge on said cylinder, a loosely mounted table or

bed having a cutting edge co-acting with said knife, means for fixing the relation between the cutting edge and the knife and means for maintaining said relation under conditions of wear.

70 8. In an envelop opener, the combination of a rotary cutter, a loosely mounted table or bed having a cutting edge co-acting with said cutter, means for fixing the relation between the cutting edge and the rotary cutter 75 and springs for maintaining said relation.

9. In an envelop opener, the combination of a rotatable cylinder having a spiral knife edge, a loosely mounted table or bed having a cutting edge co-acting with said knife edge, collars rotating with said cylinder and against which said table bears and means for keeping said table engaged with said collars.

85 10. In an envelop opener, the combination of a rotatable cylinder provided with a spiral knife edge, a table or bed upon which the envelop is supported having a cutting edge co-acting with said knife edge and guides located on the surface of said table 90 and adapted to locate an edge of the envelop with respect to the knife.

95 11. In an envelop opener, the combination of a cutter rotatable forward and backward, a table or bed having a co-acting cutting edge, means for rotating said cutter, means for automatically returning said cutter and means for stopping the return movement when the cutter has reached its original position.

100 12. In an envelop opener, the combination of a knife rotatable forward and backward, a table or bed having a co-acting cutting edge, means for rotating said knife, a spring for rotating said knife in the reverse direction after release of the rotating means and means for stopping the return movement of said knife when in its initial position.

110 13. In an envelop opener, the combination of a knife rotatable forward and backward, a table or bed provided with a co-acting cutting edge, means for rotating said knife, a spring for rotating said knife in the reverse direction after release of said rotating means and means for limiting the rotation 115 of said knife in both directions.

120 14. In an envelop opener the combination of a base, a rotary cutter mounted on said base against which the edge of the envelop is pressed, a table or bed mounted on said base upon which the envelop is supported and having a co-acting knife edge, and a receptacle on which said base is mounted, said receptacle being adapted to receive the severed edge of the envelops.

125 15. In an envelop opener, the combination of a rotary cutter against which the edge of the envelop is pressed, a table or bed upon which the envelop is supported and provided with a co-acting knife edge, a base 130

upon which said cutter and table are mounted, said base being provided with an opening located directly beneath the meeting cutter edges and a receptacle adapted to receive the severed edge of the envelope through said opening and upon which said base is mounted.

Signed at New York in the county of New York and State of New York this 18th day of July A. D 1910.
